GOLF PUTTING AND DRIVING MAT

Maximilian Richard Speiser, 17 W. 60th St.,
New York 17, N.Y.

Filed Sept. 21, 1964, Ser. No. 81,792

Term of patent 14 years

(Cl. D34—5)

FIGURE 1 is a view in perspective of a golf putting and driving mat showing my new design.

FIGURE 2 is a side elevational view thereof as might be seen from the left-hand portion of FIGURE 1.

FIGURE 3 is a side elevational view as might be seen from the upper portion of FIGURE 1.

FIGURE 4 is a top plan view thereof.

FIGURE 5 is a side elevational view as might be seen from the right-hand portion of FIGURE 4.

FIGURE 6 is a side elevational view as might be seen from the lower portion of FIGURE 4.

FIGURE 7 is a fragmentary sectional view as seen from plan 7-7 in FIGURE 4.

FIGURE 8 is a fragmentary sectional view as seen from the plan 8-8 in FIGURE 4.

I claim:

The ornamental design for a golf putting and driving mat, substantially as shown.
